United States Patent Office.

LYMAN A. GOUGH, OF YONKERS, NEW YORK.

Letters Patent No. 72,191, dated December 17, 1867.

IMPROVEMENT IN NAPHTHA-BURNER.

The Schedule referred to in these Letters Patent and making part of the same.

TO ALL WHOM IT MAY CONCERN:

Be it known that I, LYMAN A. GOUGH, of Yonkers, in the county of Westchester, New York, have invented, made, and applied to use a new and improved Naphtha-Burner; and I do declare the following to be a full, clear, and correct description of my invention, reference being had to the accompanying drawings, making part of this specification, and to the letters of reference marked thereon, in which—

Figure 1 is a sectional view of my improved burner.

Figure 2, a front view of the same.

In the drawings like parts of the invention are indicated by the same letters of reference.

The nature of my invention consists in certain improvements, as more fully hereinafter described, in the construction and operation of an improved naphtha-burner.

To enable those skilled in the arts to make and use my invention, I will proceed to describe the same.

A shows a tube, formed of copper, or any suitable metal, provided with lips *a*, formed by flattening out the metal in process of manufacture. This tube A is also provided with an opening upon its lower end, communicating with the retort B, and into which opening the end of the conical pointed screw enters. The tube A is also slotted upon its sides to receive the ends of the conductor E, as hereinafter described. B is the retort to receive the liquid from which the gas is generated by heating, which retort may be brazed on to the bottom of the tube A. The retort is provided at its back with an opening, communicating with the opening in the tube A, through which opening the gas generated in the retort enters the tube A. C is a cup, placed upon the under side of retort, to receive alcohol, or any suitable inflammable matter, to heat the retort B, before the burner is lighted, and cause gas to be generated from naphtha, or other like fluid introduced into the retort. D is a thumb-screw, provided with a conical end, inserted in bottom of retort, which screw serves to regulate the communication between the retort and tube, as when screw D is fully inserted, its conical end enters the opening in bottom of tube A, cutting off all communication between the same and the retort B. E is a conductor, formed of round copper wire, in the shape of a yolk, and so constructed that when placed over the tube A, and its ends have entered the side openings in the same, it shall fit snugly into the space between the lips *a*, closing the same. The conductor thus extends from the throat down upon each side of the tube A. This conductor is made sufficiently long and heavy to conduct the amount of heat required to heat the retort, so that gas may be generated from the liquid introduced into the same.

Such being the construction of my improved naphtha-burner, the operation may be thus described: The burner may be attached to a tube provided with a reservoir to receive the naphtha to be supplied to the retort B. The retort being supplied with naphtha, the screw D being inserted so that communication between the retort and tube is interrupted, the cup C is filled with alcohol. The alcohol being lighted, the retort is heated until gas is generated from the naphtha, or similar fluid contained in the retort B. When this is done, the screw D is unscrewed, opening communication between the retort and the tube, and allowing the gas generated in the retort to pass through the tube to the throat, where it may be ignited. As the gas comes in contact with the conductor, placed as shown, it is thrown out upon each side of the conductor, and is thus supplied to the flame, so that there are four jets, two at each side of the throat. The conductor takes up from the flame and conducts sufficient heat to the retort to heat the same, so that as fresh naphtha, or similar fluid, is introduced into or supplied to the same, the generation of gas shall go on.

The conductor is made detachable, so that access is instantly afforded to the tube, and particularly to the throat, to clean the same when required. By the use of a burner for burning naphtha and like fluids, constructed as just described, the quantity of light obtained is greatly increased, the consumption of any impurities is accomplished, and the clogging up of the tube or throat is in a great measure prevented.

Having thus described my present invention, what I claim as new, and desire to secure by Letters Patent, is—
The detachable conductor, in combination with a burner constructed and operating substantially as described.

LYMAN A. GOUGH.
